EMIL DIETZE, OF RICHMOND HILL, NEW YORK.

SPARK PLUG.

Application filed October 11, 1923, Serial No. 667,811. Renewed April 11, 1927.

This invention relates, generally, to improvements in ignition spark-plugs for internal combustion engines; and, the invention has reference, more particularly, to a construction of spark-plug provided with a novel arrangement of electrode members designed to furnish a multiple spark-gap whereby the intensity of the sparks are greatly increased, and other advantages are obtained as will subsequently appear.

The invention has for its principal object to provide a novel ignition spark-plug having a central positive electrode, a grounded negative electrode, and an intermediate electrode in novel relation to the positive and negative electrodes, whereby a plurality of spark-gaps in series are provided, all located within the firing chamber of the engine cylinder with which the spark-plug is connected, so that not only are greatly intensified sparks obtained, but fat sparks under high engine compression are assured.

The invention has for a further object to provide such a novel construction and arrangement of the electrodes of a spark-plug that the firing points are all projected into the interior of the firing chamber of the engine cylinder so that they are subjected to the influences of the hot temperatures attained in the latter, with the result that collection of oil or soot at the firing points of the electrodes is substantially eliminated so that fouling of the plugs by oil or soot or the formation of carbon, tending to render the same inoperative, is avoided.

Other objects and advantages of this invention, not at this time more particularly enumerated, will be clearly understood from the following detailed description of the same.

The invention is clearly illustrated in the accompanying drawings, in which:—

Figure 1 is a side elevation of the novel spark-plug made according to and embodying the principles of this invention; Figure 2 is a part longitudinal vertical section of the same with the core and intermediate electrode shown in elevation; Figure 3 is a complete vertical longitudinal section of the same; Figure 4 is a lower end elevation of the same, but drawn on an enlarged scale; and Figure 5 is a horizontal transverse section, taken on line 5—5 in Figure 1, and also drawn on an enlarged scale.

Similar characters of reference are employed in all of the hereinabove described views to indicate corresponding parts.

Referring now to said drawings, the reference character 1 indicates the main body of the spark-plug, which is provided at its lower end with an externally threaded portion 2, by means of which the spark-plug is operatively connected with the engine cylinder it is to serve. Said main body 1 is also provided with the usual longitudinal opening extending therethrough from end to end, and intermediate the ends of which is disposed an internal annular shoulder 3 which divides said opening into an upper chamber 4, open at its upper end and internally threaded at said open end, and a lower chamber 5, open at the lower end of said portion 2. The upper side of said annular shoulder 3 provides a seat 6 for supporting the detachable porcelain insulator core 7 which in turn supports the positive electrode 8 of the spark-plug. Said porcelain core 7 is provided, at a suitable point intermediate its upper and lower end portions, with an annular enlargement or external shoulder 9, the lower side of which is supported upon said seat 6. A suitable gasket 10 is interposed between said shoulder 9 and said seat 6 in the usual manner. Said porcelain core 7 is secured against displacement from normal assembled relation to said main body by means of an externally threaded union 11, which is screwed into the internally threaded chamber 4 so as to engage the upper side of said enlargement or shoulder 9 of said porcelain core. A suitable gasket 12 is interposed between the union 11 and said enlargement or shoulder 9 in the usual manner.

Said positive electrode comprises a rod, preferably made of manganese nickel, which is disposed to extend longitudinally or axially through said porcelain core 7, with its lower free end 13 projecting downwardly beyond the lower extremity of said core. The upper end portion of said core 7 is provided with an externally threaded stud 14, preferably of reduced diameter. Engaged upon said stud 14 is a terminal cap 15, which is provided with beaded threads 16 for coacting with the threads of said stud 14. Projecting upwardly from the cap 15 is a screw-threaded post 17 upon which is engaged a binder nut 18 for holding an electric cur-

rent supply wire in electrical connection with said cap. The upper end of said positive electrode 8 extends into the body of said cap 15 so as to both electrically and mechanically connect the one with the other. The upper extremity of the core 7 is provided with a depressed or dish-shaped cavity 19 which affords a receiving space for a suitable cement 20 whereby the cap is held against accidental loosening and displacement from the core. The cement will also work into the cavities intermediate the threads of the stud 14 and the beaded threads 16 of the cap 15, so as to afford an additional binder between the cap and the core.

The negative electrode of the spark-plug is connected with the lower extremity of the portion 2 of said main body 1 so as to be grounded electrically therewith, and the same comprises an annular terminal member or ring 21 which is disposed in concentric relation to and spaced outwardly from the lower free end 13 of the positive electrode 8. Said ring 21 is supported by an inverted conical flange-portion 22, the body of which is cut away to provide a plurality of vent openings 23. Said lower extremity of the portion 2 of said main body 1 is provided with an annular retaining flange 24, within the embrace of which the upper marginal portions 25 of said flange-portion 22 is engaged, whereupon said retaining flange 24 is turned or clenched around the flange-portion 22, to thus mechanically affix said negative electrode to the spark-plug body while at the same time electrically grounding the negative electrode upon said main body. Said negative electrode is preferably made of manganese nickel.

Said porcelain core 7 is so disposed that its lower portion projects downwardly through the lower chamber 5 of the main body 1 but terminates short of the lower open end of the latter. The extremity of said lower portion of the core 7 is provided with an annular shoulder or enlargement 26. The reference character 27 indicates the main body of an intermediate electrode, said main body being preferably of tubular form and tapering toward its lower end. Integrally connected with the upper end of said main body 27 is a ferrule member 28 which is mounted upon the shoulder or enlargement 26 of the core, whereupon the upper marginal portion of said ferrule member 28 is turned inwardly or clenched over the upper side of said shoulder or enlargement 26, to thus securely support the intermediate electrode in operative assembled relation. The lower end of said body 27 of the intermediate electrode terminates opposite and in concentrically outwardly spaced relation to the lower extremity 13 of said positive electrode 8, thus providing an intermediate spark-gap 29. Integrally connected with

said lower end of said main body 27 of the intermediate electrode are a plurality of outwardly deflected radial terminal projections 30, the ends of which are opposed to and inwardly spaced relative to the ring-like terminal of said negative electrode 21, to thereby provide intermediate said projections 30 and ring 21 additional spark-gaps 31 in series relation to the spark-gap 29. The main body 27 of said intermediate electrode is cut away at suitable points to provide vents 32. Said intermediate electrode is insulated by the core 7 from both the positive and negative electrodes of the spark-plug, and the same is also preferably made of manganese nickel.

In operation the novel construction of the spark-plug above described functions in the following manner:

The current is supplied to the positive electrode in the usual manner and in proper timed relation to the piston strokes within the engine cylinder with which it is connected. When the vaporized fuel is introduced into the engine cylinder and compressed by the compression stroke of the piston, the same is caused to flow through the vents 23 and 32 so as to surround the terminal portions of the electrodes. The electrical current is thereupon caused to enter the positive electrode 8, whereupon it immediately jumps the gap 29 to the intermediate electrode, and thence jumps from the terminal projections 30 across the gaps 31 to the negative electrode 21. The gaps 29 and 31 being in series, the electrical effect is to greatly intensify the sparks or electrical arcs produced, thus assuring at least two intense and hot blue white sparks or flashes, both of which are effective in assuring the prompt and thorough ignition of the fuel charge compressed in the engine cylinder. Owing to the great intensity of the sparks produced, and the electrical force of the same as they strike across the spark-gaps, the same will not be impeded by the high pressures resultant upon the compression of the fuel. Another advantage of the novel arrangement of electrodes providing a plurality of spark-gaps in the firing chamber of the engine cylinder, is that the disposition of the electrode terminals is such that they are projected into the said firing chamber so that upon ignition of the fuel they are subjected to the high temperatures induced by the fuel combustion, and consequently collection of oil or soot on the terminals is substantially eliminated, so that the terminals are maintained bright and clean.

Another advantage of my novel arrangement of electrodes to provide a plurality of spark-gaps in series, is that short-circuiting of the plug terminals is less likely to occur, for if, under exceptional circumstances one gap should be closed or short circuited and
